COMMUNICATION SYSTEM

Richard H. Campbell, Racine, Wis., assignor to
 Webster Electric Company, Racine, Wis., a corporation of Delaware

Application March 25, 1940, Serial No. 325,670

6 Claims. (Cl. 179—1)

The present invention relates to communication systems and has for its primary object the provision of an improved system for disseminating information from what may be termed an information center to a plurality of outlying substations.

In department stores, banks, and other establishments of similar nature, records of transactions, etc., are ordinarily kept at a central location distant from places where the information is required in a multitude of everyday transactions. Various arrangements have been perfected in the past for making the information available, but they have been open to objections of one sort or another.

The present invention has for its object the provision of a system whereby information from a central location may be disseminated readily and quickly to outlying locations upon request.

A further object of the present invention is to provide a system that is continuously conditioned for instantaneous operation and one in which a person at a substation has merely to pick up a combined receiver and microphone to place himself in communication with a person at the information center.

A further object of the invention is so to arrange the system that only the operator at a substation can hear the information sent from the information center, and the person at the information center may hear and speak even when at a considerable distance from that portion of the apparatus forming the system located at the center.

A further object of the invention is to provide a system wherein each substation is provided with a busy signal and with means for rendering operative all the busy signals whenever the particular substation is placed in communication with the information center.

Other objects and advantages of the invention will become apparent from the ensuing description in the course of which reference is made to the accompanying drawing, the single figure of which schematically represents one embodiment of the invention.

Referring now to this figure, the information center is indicated by reference character 1 and the outlying substations by reference characters 2 and 3. Only two substations are illustrated, but the system may comprise any number, as will appear more fully hereinafter. For the purpose of better describing the invention, it is assumed that the information center is the credit record room

of a department store, and the substations 2 and 3 are department managers' offices or desks.

The apparatus at the information center is of a type conditioned for instantaneous operation and comprises a microphone 10 and a loudspeaker 12 connected, respectively, to the input and output of amplifiers 14 and 16. The amplifiers are preferably, but not necessarily, conditioned for instantaneous operation; i. e., they are normally supplied with power from a source not shown. The microphone and loudspeaker are so constructed and arranged with respect to the amplifiers that a person located anywhere in the information center, which may be a room or a portion of a room where the records are kept, may speak in a normal tone of voice and be heard by persons at the substations and may hear what information is desired. The amplifiers, however, need not be located directly at station 1, as illustrated—they may be located at some convenient central location.

The information center is connected to the substations through incoming and outgoing circuits. The former consists of a conductor 18 and a common conductor 20 (which may be a grounded shield for the other conductors), and the latter of conductor 22 and the common conductor 20.

Substations 2 and 3 are each provided with two switches, one for controlling the connections of the voice receiving and transmitting means thereat to the amplifiers at the information center and partly completing an energizing circuit for busy signal means, and the second for completing the energization of the busy signal means.

Thus, substation 2 is provided with a communication circuit and busy signal circuit controlling switch 24 of the normally open push button type and a signal circuit controlling normally open switch 26 actuated by a translating device 28.

Identical switches 30 and 32 are provided at substation 3, and at any other stations which may be included in the system. Switch 32, like switch 26, is actuated by a translating device 34. The signal devices preferably take the form of electric lamps 35.

Before proceeding with a detailed discussion of the circuits, it may be well to point out that the translating devices 28 and 34 at substations 2 and 3, respectively, comprise receivers 36 and 38 and transmitters or microphones 40 and 42. The translating devices 28 and 34 preferably take a form resembling that of the ordinary telephone hand set and when not in use may be placed upon suitable supports, not shown, and when so supported maintain the switches 26 and 32 in the

open circuit positions in which they are illustrated. When the translating devices are picked up for use, the switches are automatically closed.

The combined communication and signal circuit controlling switch 24 at substation 2 normally occupies a position such that the receiver 36 and microphone 40 are disconnected from their respective amplifiers and the signal control circuit is broken. The switch is operable manually to a displaced position to connect the receiver 36 to the output of amplifier 14 and microphone 40 to the input of amplifier 16, and also to condition the signal control circuit for closure by switch 26. Receiver 36 is connected to the output of amplifier 14 by movable switch blade 44, microphone 40 is connected to the input of amplifier 16 by a second movable switch blade 46, and the signal circuit is conditioned for closure by switch 26 by a third movable switch blade 48. The movable switch blades 44, 46 and 48 are operable simultaneously by a push button 50, as clearly indicated in the drawing.

The receiver 36 is connected to the output of amplifier 14 through a circuit, including the amplifier output conductor 22, a branch conductor 52 leading to substation 2, movable switch blade 44, a conductor 54 leading to the receiver, and thence back to the amplifier output through conductors 56, 58 and the previously mentioned common conductor 20.

The microphone 40 is connected to the input of amplifier 16 through a circuit including the amplifier input conductor 18, a branch conductor 60, movable switch blade 46, a conductor 62 leading to the microphone, and thence back to the amplifier input through conductor 64 and the previously mentioned conductors 58 and 20.

The signal circuit is conditioned for closure by switch 26 through a circuit including a local source of power, illustrated as a battery 66, located at some suitable central location, a signal circuit controlling solenoid 68, conductor 70, movable switch blade 48, a conductor 72 leading therefrom to switch 26, and conductor 72 leading from the latter back to the battery.

Thus, whenever switch 24 is depressed and the translating device 28 is picked up for use, stations 1 and 2 are connected for two-way communication and the signal circuit controlling solenoid 68 energized.

The energization of solenoid 68 results in the supply of power to the lamps 35 from a suitable source, not shown, through conductors 74 and a normally open switch 76, closed upon energization of solenoid 68. The lamps 35 are all connected in parallel so that all are supplied with power simultaneously. The lamp 35 at substation 2 is connected to the power supply by conductors 78 and the lamp 35 at substation 3 by conductors 80, the lamps at other stations, not shown, by conductors 82.

The apparatus at substation 3 is connected in parallel to the apparatus at substation 2 so that when the switch 30 at substation 3 is depressed and the translating device 34 thereat is picked up, the receiver 38 is connected to the output of amplifier 14, microphone 42 is connected to the input of amplifier 16 and the signal circuit controlling solenoid is energized to supply energy to the signal lamps 35 at the various substations.

Receiver 38 is connected to the output of amplifier 14 through a circuit including the output conductor 22, branch conductor 84, movable switch blade 86 of the push button switch 30, and conductor 86 leading to receiver 38, and

from thence back to the amplifier output through conductors 88, 90, and the previously mentioned common conductor 20. The microphone 42 is connected to the input of amplifier 16 through a circuit including input conductor 18, branch conductor 92, movable switch blade 94 of the push button switch 30, and conductor 96 to the microphone, and from thence back to the input through conductor 98 and the previously mentioned conductors 90 and 20. The signal circuit controlling solenoid 68 is energized through a circuit including the battery 66, the solenoid winding 68, conductor 100 leading to the third movable switch blade 102 of push button switch 30, conductor 104 leading from the latter to switch 32, and conductor 106 leading from this switch back to the battery 66.

The remaining stations of the system, which have not been illustrated, are connected in parallel with substations 2 and 3 through branch conductors 108, 110 and 112 forming part of the interstation communication circuits; conductors 114 and 116 forming part of the signal control circuit; and the previously mentioned conductors 82 through which the lamps are supplied with energy.

Under normal conditions and when the system is not being utilized for the transmission of communication, the various switches assume the positions in which they are indicated, and the amplifiers 14 and 16 are supplied with power so that any remote stations may communicate with the information center merely by depressing the push button switch thereat and picking up the translating device. It may be remembered that it was assumed that the information center was located in a record room of a department store and the substations 2 and 3 were located at the offices or desks of department managers. If the department manager at substation 2 desires some information from the credit room, he depresses the push button switch 24 and picks up the translating device (or vice versa, for that matter), thereby placing the microphone and receiver at the substation in direct communication with the microphone and receiver at the credit room through the amplifiers 14 and 16, through circuits that have been previously traced in detail. Simultaneously, the lamps at all the substations are supplied with power through previously traced circuits to give an indication that the system is in use. The other department managers will, therefore, not try to communicate with the credit room as long as the lamps are energized.

However, no harm is occasioned even if two of the credit managers try to communicate with the credit room at the same time.

While only a single embodiment of the invention has been illustrated and described, it should be understood that it is susceptible of other and further modifications. For instance, certain features of the invention are adapted for use in systems in which different types of receiving and transmitting means are used and where different types of interstation circuits are utilized. It should be understood further that the specific embodiment is not intended to limit the scope of the invention in any way.

What I claim is new and wish to secure by United States Letters Patent is, as follows:

1. In a communication system, the combination including, a pair of amplifiers each having an input and an output, a station having a loud-speaker connected to the output of a first

of said amplifiers, and a microphone connected to the input of the second of said amplifiers, a plurality of substations remote from the first station, receivers and microphones at each of said substations, a pair of interstation circuits leading from said first station to said substations and connected to the input and output of said first and second amplifiers, respectively, and means including normally open switches at each substation for connecting the microphones and receivers thereat to the input of the first amplifier and output of the second amplifier, respectively, through said interstation circuits.

2. In a communication system, the combination including, a pair of normally operative amplifiers each having an input and an output, a station having a loudspeaker connected to the output of a first of said amplifiers and a microphone connected to the input of the second of said amplifiers, a plurality of substations remote from the first station, receivers and microphones at each of said substations, a pair of interstation circuits leading from said first station to said substations and connected to the input and output of said first and second amplifiers, respectively, and means including normally open push button switches at each substation for connecting the microphones and receivers thereat to the input of the first amplifier and output of the second amplifier, respectively, through said interstation circuits.

3. In a communication system, the combination including, a pair of amplifiers each having an input and an output, a station having a loudspeaker connected to the output of a first amplifier and a microphone connected to the input of the second amplifier, a second station remote from the first station, a translating device including a receiver and a microphone, signal means and a signal circuit at the second station, an interstation communication circuit, a manually operable normally open communication circuit and signal circuit controlling switch at the second station operable to a displaced position to connect the microphone to the input of said first amplifier and the receiver to the output of said second amplifier through said interstation circuits, and to condition said signal circuit for closure, and a normally open signal circuit completing switch at the second station operable by said translating device.

4. In a communication system, the combination including, a pair of normally operative amplifiers each having an input and an output, a station having a loudspeaker connected to the output of a first amplifier and a microphone connected to the input of the second amplifier, a second station remote from the first station, a translating device of the telephone type including a receiver and a microphone, signal means

and a signal circuit at the second station, an interstation communication circuit, a manually operable normally open communication circuit and signal circuit controlling switch at the second station operable to a displaced position to connect the microphone to the input of said first amplifier and the receiver to the output of said second amplifier through said interstation circuits, and to condition said signal circuit for closure, and a normally open signal circuit completing switch at the second station operable by said translating device.

5. In a communication system, the combination including, a pair of amplifiers each having an input and an output, a station having a loudspeaker connected to the output of a first of said amplifiers and a microphone connected to the input of a second of said amplifiers, a plurality of substations remote from said first station, translating devices including receivers and microphones at each of said substations adapted to occupy a predetermined position when not in use, interstation communication circuits, a signal circuit extending between said substations, signal means at each substation, a normally open switch at each substation manually operable to connect the microphone thereat to the input of the first of said amplifiers and the receiver thereat to the output of the second of said amplifiers and partly to complete said signal circuits, and switch means at each substation operable by the translating device thereat when it is removed from said predetermined position for use to complete said signal circuits and render operative the signal means at all stations.

6. In a communication system, the combination including, a pair of normally operative amplifiers each having an input and an output, a station having a loudspeaker connected to the output of a first of said amplifiers and a microphone connected to the input of a second of said amplifiers, a plurality of substations remote from said first station, translating devices including receivers and microphones at each of said substations adapted to occupy a predetermined position when not in use, interstation circuits, a signal circuit extending between said substations and comprising a single solenoid, signal means at each substation operable upon energization of said solenoid, a normally open push button switch at each substation manually operable to connect the microphone thereat to the input of the first of said amplifiers and the receiver thereat to the output of the second of said amplifiers and partly to complete said signal circuits, and switch means at each substation operable by the translating device thereat when it is moved from said predetermined position to complete a circuit to energize said solenoid and thereby render operative the signal means at all stations.

RICHARD H. CAMPBELL.
